CLAIM

The ornamental design for a belt bracket of a powered air purifying respirator, as shown and described.

DESCRIPTION

FIG. 1 is a perspective view of a belt bracket of a powered air purifying respirator, showing our new design;

FIG. 2 is a front view thereof;

FIG. 3 is a back view thereof;

FIG. 4 is a bottom plan view thereof;

FIG. 5 is a top plan view thereof;

FIG. 6 is a left side view thereof; and,

FIG. 7 is a right side view thereof.

In these drawings, the solid lines illustrate the claimed ornamental design, whereas the broken lines illustrate environmental features that form no part of the claimed ornamental design.
